TYPOGRAPHICAL SLUG CASTING MACHINE

William Fairall Gorse, Altrincham, and Richard Henry Scott, Enfield, England, assignors to Linotype and Machinery Limited, London, England, a company of England

Application March 17, 1934, Serial No. 716,115
In Great Britain April 8, 1933

14 Claims. (Cl. 199—49)

This invention relates to typographical slug casting machines such as those known commercially under the trade mark "Linotype", wherein circulating matrices are composed in line, the line transferred to a vertically movable transporter or so-called first elevator, which is lowered to present the line to the mould for casting, and after casting raised to a position from which the matrices are transferred from the first elevator 5 to a second elevator for delivery to the distributing mechanism.

On passing into the first elevator the leading matrix of a line abuts against a resistant member slidably mounted in the first elevator, after 15 passing a pair of retaining pawls carried at the receiving end of the elevator, which pawls engage behind the last or terminal matrix of the line, the leading and terminal matrices being thus held against twisting or displacement while in the first elevator. When, however, quadding or centring devices are employed, in the use of which 20 a matrix line may be shifted endwise in the first elevator prior to casting, the terminal matrix of the line is thus carried away from, and deprived of the support of, the retaining pawls. In 25 these circumstances, there is a liability for the matrices at the end of the line to become displaced, particularly during the raising of the first elevator from the casting to the upper trans- 30 fer position.

According to the present invention this difficulty is avoided by providing matrix retaining means which, although normally located at the receiving end of the first elevator, are movable 35 endwise therein simultaneously with endwise movement of the line effected for quadding or centring so that said matrix retaining means are kept in engagement with the terminal matrix of a line whatever the position of the latter in the first elevator.

In carrying out the invention, the matrix-retaining means are held out of operative position at the receiving end of the elevator during the delivery of the line thereto, and at the same time 45 locked against longitudinal movement. On completion of the delivery of the line, the matrix-retaining means are restored to operative position in engagement with the terminal matrix of the line, and released for longitudinal movement.

The invention is hereinafter more particularly 50 described with reference to the accompanying drawings, which illustrate one constructional form of apparatus by which the invention may be carried out.

In the said drawings:—

Figure 1 is a horizontal sectional view of the first elevator head, the section, as to the left-hand part of the figure being taken in the plane indicated by the line A—A of Figure 4, and as to the right-hand part of the figure, in the plane indicated by the line B—B of Figure 3, the devices being represented in normal position;

Figure 2 is a view similar to Figure 1 showing the position of the devices during the delivery of a composed line to the elevator;

Figure 3 is an end elevation of the elevator head as viewed from the right-hand side of Figures 1 and 2;

Figure 4 is a vertical section taken on the line 4—4 of Figure 1, and

Figure 5 is a vertical section taken on the line 5—5 of Figure 1.

In the constructional form of the invention illustrated, the matrix retaining means are in the form of spring pawls 3 located at the receiving 20 end of the elevator 2, which, except as hereinafter described, correspond with the longitudinally fixed matrix retaining pawls usually provided for engagement with the terminal matrix of a line. The elevator is also provided with a line-resistant 25 member 4 of substantially known form, against which the leading matrix of a composed line abuts on delivery of the line 1 to the elevator, as indicated in Figure 2. The resistant member 4 slides in grooves in the front and rear walls 30 of the elevator head. In the normal operation of such devices as heretofore used the leading and terminal matrices of the line are held against displacement by the said resistant member 4 and pawls 3 respectively, but the pawls are secured 35 in the elevator head itself. Consequently, as the line is moved inwardly by the right-hand vise jaw during quadding or centring, the terminal matrix is carried away from the pawls 40 and when the elevator rises after casting to remove the line from between the vise jaws, the terminal matrix is without support.

According to the arrangement illustrated the retaining pawls 3 are utilized for the support of the terminal matrix irrespective of the position 45 of the line in the elevator. For this purpose the pawls 3 are secured to rails 5 longitudinally slideable in the elevator head, and these rails 5 constitute virtually extensions of the sliding resistant member 4. The pawls 3 are depressed into 50 recesses 6 in the elevator head by the leading matrix of a line entering the elevator, and at their outer ends are provided with shoulders 7 adapted to be engaged by detents 8 which serve 55 to hold the pawls in the withdrawn position. The

pawls are also provided with shoulders 9 which engage the left-hand walls 6^a of the recesses 6 when the pawls are withdrawn, thus cooperating with the detents 8 to retain the pawls in their withdrawn position at the receiving end of the elevator, as shown in Figure 2. The rails 5 to which the pawls 3 are secured are thus held against longitudinal movement during the delivery of the line to the elevator, while the resistant member 4 is moved for example from the position in which it is shown in Figure 1 to that in which it is shown in Figure 2. To permit this movement of the resistant member 4 relatively to the rails 5, the latter are frictionally secured to 15 the said member. The desired connection is conveniently effected by means of studs 10 passing through slots 11 in the respective arms of the resistant member 4 and bearing thereon through friction washers 12, the heads of the studs 10 and 20 the washers 12 lying within longitudinal recesses 13 formed in the inner faces of the resistant member 4.

When delivery of the line to the first elevator is completed, the known delivery slide right-hand finger 14 releases the detents 8, thus permitting the pawls 3 to return to their active position in which they engage behind the terminal matrix of the line.

As shown in Figure 3, the detents 8 are carried 30 on horizontal pivots 15 in the elevator head and are held in active position by springs 16 acting upon the detents above the pivot. At their upper ends the detents 8 are provided with lateral extensions 17 which lie in the path of the delivery finger 14 to enable the latter as it enters the first elevator at the end of the line delivery stroke to effect the release of the detents as above mentioned.

It will now be understood that when a line of 40 matrices 1 is to be quadded or centred and the line is for this purpose moved towards the left as viewed in Figures 1 and 2, the line resistant member 4 will be taken with it and also the rails 5 and pawls 3, since the latter are free to move 45 longitudinally, and will be so moved through the stud and washer connection 10, 12. The pawls 3 will thus be retained in contact with the terminal matrix of the line throughout its movement along the elevator, and during the raising of the elevator after casting.

As is well known, the line resistant member 4 normally occupies the position in which it is shown in Figure 1 and is automatically returned to that position by means of the upper transfer 55 slide by which the matrix line is delivered from the elevator to the distributor. This arrangement, being well known, is not illustrated, but it should be explained that the mechanism in question is utilized for also returning the pawls 3 to the line receiving position.

To ensure the necessary relative movement between the line resistant member 4 and rails 5 during such restoration of the parts to normal position, studs 18 are provided near the leftward extremity of the rails 5, which studs project outwardly from the said rails towards the elevator walls, and stop pins 19 are secured to the said walls to co-operate with the studs 18 to limit the rightward movement of the rails 5. It is also desirable to provide means for limiting the leftward movement of the line resistant member 4, and in the constructional example shown such means consist of stop pins 20 fixed in the elevator head.

75 The mechanism above-described and illus-

trated in the accompanying drawings ensures adequate support for the terminal matrix of a line in the elevator throughout the operation of the latter from the moment when the line is delivered to the elevator until it is transferred therefrom for distribution. It is to be understood, however, that the mechanism in question is described and illustrated merely as a convenient example, and that modifications in the form of the devices may be made without departing from the invention.

Having described our invention, we declare that what we claim and desire to secure by Letters Patent is:—

1. In a typographical slug casting machine, the combination with a transporter in which a composed line of matrices is carried to and from casting position, of matrix-retaining means normally located at the receiving end of the transporter, to engage the last composed matrix of a line, said means being movable endwise in the transporter simultaneously with endwise movement of the composed line.

2. In a typographical slug casting machine, the combination with a transporter in which a composed line of matrices is carried to and from casting position, of matrix-retaining means normally located at the receiving end of the transporter and movable to an inoperative position by the leading matrix of a line entering the transporter, means adapted to restore the matrix-retaining means to operative position only when the last composed matrix of a line enters the transporter, and means permitting endwise movement of said matrix-retaining means when so restored.

3. In a typographical slug casting machine, the combination with a transporter in which a composed line of matrices is carried to and from casting position, of matrix-retaining means normally located at the receiving end of the transporter and movable to an inoperative position by the leading matrix of a line entering the transporter, means adapted to restore the matrix-retaining means to operative position only when the last composed matrix of a line enters the transporter, means permitting endwise movement of said matrix-retaining means when so restored and means adapted to lock said matrix-retaining means against endwise movement when in the inoperative position.

4. In a typographical slug casting machine, the combination with a transporter in which a composed line of matrices is carried to and from casting position, of a resistant member slidable endwise in the transporter by the engagement therewith of the leading matrix of an advancing line, matrix-retaining means normally located at the receiving end of the transporter to engage the last composed matrix of a line and yieldable means connecting said matrix-retaining means and resistant member so as to permit relative longitudinal movement thereof.

5. In a typographical slug casting machine, the combination with a transporter in which a composed line of matrices is carried to and from casting position and a resistant member slidable endwise in the transporter by the engagement therewith of the leading matrix of a line, of matrix-retaining means movable longitudinally of the transporter and normally located at the receiving end thereof to engage the last composed matrix of a line, said matrix-retaining means being movable to an inoperative position by the leading matrix of a line entering the transporter,

5 a locking device for holding the matrix-retaining means in inoperative position and against longitudinal movement, means adapted to release the locking device when the last composed matrix of a line enters the transporter, and yieldable means connecting said matrix-retaining means and resistant member to permit relative longitudinal movement thereof.

10 6. In a typographical slug casting machine, the combination with a transporter in which a composed line of matrices is carried to and from casting position, of spring pawls normally located at the receiving end of the transporter to engage the last composed matrix of the line and rails longitudinally slidable in the transporter to which said pawls are secured.

15 7. In a typographical slug casting machine, the combination with a transporter in which a composed line of matrices is carried to and from casting position, of spring pawls normally located at the receiving end of the transporter to engage the last composed matrix of the line after depression to an inoperative position by the advance of a line into the transporter, rails longitudinally slidable in the transporter to which said pawls are secured, spring detents at the receiving end of the transporter adapted to lock the pawls in the inoperative position during said advance of the line, and abutments on the transporter adapted to engage the pawls and prevent longitudinal movement of the rails when the pawls are in the inoperative position.

20 8. In a typographical slug casting machine, the combination with a transporter in which a composed line of matrices is carried to and from casting position and a line-delivery finger adapted to advance a composed line into the transporter, of spring pawls normally located at the receiving end of the transporter to engage the last composed matrix of the line after depression to an inoperative position by the advance of the line, rails longitudinally slidable in the transporter to which said pawls are secured, spring detents at the receiving end of the transporter adapted to lock the pawls in the inoperative position during the advance of the line and to be released by the line delivery finger to unlock said pawls, and abutments on the transporter adapted to engage the pawls and prevent longitudinal movement of the rails when the pawls are in the inoperative position.

25 9. In a typographical slug casting machine, the combination with a transporter in which a composed line of matrices is carried to and from casting position, of a resistant member comprising rails slidable endwise in the transporter by the engagement therewith of the leading matrix of an advancing line, spring pawls normally located

30 at the receiving end of the transporter to engage the last composed matrix of a line, rails longitudinally slidable in the transporter to which said pawls are secured, and a yielding connection between the pawl-carrying rails and the rails of the resistant member comprising studs secured to the pawl-carrying rails and passing through slots in the resistant member rails, and friction washers interposed between said studs and the resistant-member rails.

35 10. In a typographical slug casting machine, a combination according to claim 9, characterized by stops on the pawl-carrying rails and stops on the transporter walls co-operating therewith to limit longitudinal movement of the said rails towards the receiving end of the transporter.

40 11. In a typographical slug casting machine, a combination according to claim 9, characterized by stops on the transporter adapted to limit the longitudinal movement of the resistant member rails in a direction away from the receiving end of the transporter.

45 12. In a typographical slug casting machine, the combination with a transporter in which a composed line of matrices is carried to and from casting position, of matrix-retaining means normally located at the receiving end of the transporter, to engage the last composed matrix of a line, said means being movable endwise in the transporter to correspond to different shifted positions of the composed line therein.

50 13. In a typographical slug casting machine, the combination with a transporter in which a composed line of matrices is carried to and from casting position, of a resistant member carried by the transporter and adapted to engage the leading matrix of the composed line, and matrix-retaining means also carried by the transporter and adapted to engage the last composed matrix of the line, said resistant member and matrix-retaining means both being movable endwise in the transporter to accommodate different shifted positions of the line therein.

55 14. In a typographical slug casting machine, the combination with a transporter in which a composed line of matrices is carried to and from casting position, of a resistant member carried by the transporter and adapted to engage the leading matrix of the composed line, and matrix-retaining means also carried by the transporter and adapted to engage the last composed matrix of the line, said resistant member and matrix-retaining means both being movable endwise in the transporter by the composed line when the latter is shifted from one position to another therein.

WILLIAM FAIRALL GORSE.
RICHARD HENRY SCOTT.
